(57) **CLAIM**

The ornamental design for a cantilevered exercise device, as shown and described.

DESCRIPTION

FIG. 1 is a perspective view of a cantilevered exercise device.

FIG. 2 is a side view of the exercise device of FIG. 1.

FIG. 3 is an opposite side view of the exercise device from FIG. 2.

FIG. 4 is a top view of the exercise device of FIG. 1.

FIG. 5 is a bottom view of the exercise device of FIG. 1.

FIG. 6 is a front view of the exercise device of FIG. 1.

FIG. 7 is a back view of the exercise device of FIG. 1.

FIG. 8 is a perspective view of the exercise device with the cylindrical member in a different position relative to the handle.

FIG. 9 is a perspective view of the exercise device with the cylindrical member in a different position relative to the handle; and,

FIG. 10 is a perspective view of the exercise device with the cylindrical member in a different position relative to the handle.

The broken lines in FIGS. 1–10 are for illustrative purposes only and form no part of the claimed design. The broken lines in the cylindrical member represent knurled lines that are not claimed as part of the design. The design and shape of the exercise device remains the same while the cylindrical member location relative to the handle can be altered.
